ILLINOIS.

OIL BURNER.

Application filed May 5, 1923. Serial No. 636,829.

Our invention relates to improvements in oil burners, and is particularly concerned with, though not limited to, improvements in that type of oil burner embodying a 5 rotary atomizing or forming the oil in a fine spray which is subsequently mixed with the proper amount of air for combustion.

Heretofore, in the operation of burners of this type, considerable difficulty has been 10 experienced by the formation of carbonaceous deposits upon the bottom and walls of the fire box due to the incomplete combustion of the fuel itself, and to the fact that the oil was not completely atomized before 15 it struck the walls of the fire box. If a deposit of this character once starts to build up, it usually continues until it seriously interferes with the operation of the burner, and requires shutting down the burner until 20 the deposit can be removed. This is a rather difficult matter and has always been a source of considerable expense in the maintenance of burners of this type.

The objects of our invention are to provide 25 means co-operating with the atomizer in such manner as to direct the air currents, to be mixed with the atomized fuel, away from the walls, and particularly from the bottom of the fire box, so as to thoroughly 30 atomize the fuel and mix it with the air to form a completely combustible mixture before the oil has had a chance to contact with and become deposited upon the walls of the fire box.

Another object of our invention is to provide 35 means, such as described, which will permit easy and accurate adjustment of the supply of air.

A further object of our invention is to provide 40 means, such as described, which will not be rendered inoperative by the deposit of carbon upon the means itself.

A still further object of our invention is to provide means, of the character described, 45 which is simple in construction and economical to manufacture.

Other objects of our invention will appear as this description progresses, reference 50 being had to the accompanying drawing, which shows our invention embodied in an oil burner shown in central vertical section,

a portion of the fire box also being shown in section.

We have illustrated our invention in the accompanying drawing as forming part of 55 an oil burner comprising the head 5, in which is rotatably mounted a hollow spindle 6 driven by the bevel pinion 7 and the bevel gear 8. The bevel gear 8 is driven by a motor, not shown, through the shaft 9. A 60 tubular outwardly flaring atomizing nozzle 10 is secured to the upper end of the spindle 6, and the flaring portion thereof carries a plurality of radially extending fan blades 11 for supplying air to the oil spray dis- 65 charged from the atomizing edge 12 of the atomizer.

A stand pipe 13, extending upwardly through the hollow spindle 6 and supplied with oil by the pipe 14, is provided at its 70 upper end with downwardly directed discharge tubes 15 which discharge the oil into the annular space 17 formed between the upper end of the spindle and the thimble 18. When the atomizer is rotated, the oil 75 discharge into this annular space moves upwardly under centrifugal force along the inner surface of the atomizer, and is discharged from the edge 12 in a fine spray.

To render this fine spray completely combustible, it is necessary to mix it with the proper quantity of air, and for this purpose we provide the neck ring 19 which projects through the bottom 20 of the fire box, which is preferably formed of fire clay. A plurality of rollers 21 are supported by the neck ring 19, only one being shown in the present case. A sleeve 22 is provided with inclined cam faces 23 which rest upon the rollers 21 so that when the sleeve 22 is rotated by 80 any suitable means, such, for instance, as a link 24, the inner end of which is secured to a pin 25 projecting downwardly from the sleeve 22, the sleeve will be vertically adjusted. The upper edge of the sleeve 22 is 85 provided with a plurality of equally spaced notches 26 forming teeth 27, the inner edges of which are beveled outwardly, as shown at 28.

For controlling the air supply to the oil 100 spray by the fan blades 11, we provide the air controlling ring 29 which has a central

opening 30 slightly larger in diameter than the fan blades. An annular depression 31 is formed in the upper face of the ring 29, the radius r of this depression being substantially equal to the diameter d of the atomizer at its atomizing edge. We have found that when the diameter d' of the annular depression 31 is made less than twice the diameter d of the atomizing nozzle, it functions better than when this ratio is increased. We have found that this diameter d' varies from 6" for an atomizer having a diameter d equal to 3", to 7 $\frac{1}{4}$ " for an atomizer having a diameter d equal to 4". Where the latter diameter is equal to 3 $\frac{1}{2}$ ", we have found that the diameter d should be approximately 6 $\frac{1}{2}$ ". The depth d'' of the depression varies with the diameter of the atomizer, being larger for small atomizers than for larger atomizers. Our experiments have demonstrated that for an atomizer 3" in diameter, this distance should be approximately $\frac{5}{16}$ "; for an atomizer 3 $\frac{1}{2}$ " in diameter, $\frac{1}{4}$ ", and for an atomizer 4" in diameter, 25 $\frac{3}{16}$ ".

Experiments have demonstrated that the shape of the periphery 29 has an important bearing upon the direction of air currents after they leave the controlling ring, and that if the edge of this ring is made vertical, the flame has a tendency to swirl down into contact with the bottom 20 of the fire box, depositing carbon thereon. After numerous experiments, we have found that the best results are obtained by beveling the edge of the ring, as shown at 32. This bevel becomes smaller with increase in diameter of the ring, the angle a being approximately 30° for a 3" burner, 25° for a 3 $\frac{1}{2}$ " burner, 40 and 20° for a 4" burner, this angle becoming still less as the diameter of the burner increases.

We have found through experiment that if the ring 29 is adjusted so that the edge 33, formed by the annular depression 31 and the bevel 32, is approximately in the same plane as the atomizing edge of the atomizer, considerable variation in the quantity of fuel or oil supply to the atomizer may be made without varying the adjustment of the sleeve 22. At this point, the upper edge of the neck ring 19 has uncovered a portion of the notches 26 in the sleeve 22, thereby permitting air to flow through these notches and mix with the mixture previously formed by the atomized fuel and the air discharged from the fan blades 11. Apparently, the amount of fuel burned automatically controls the natural draft through the notches 26 so as to maintain substantially the correct proportion between the oil and the air.

For the purpose of centering the air controlling ring upon the sleeve 22, we provide the lower face thereof with the downwardly extending beveled ring 34, which rests upon

the beveled faces 28 of the teeth 27. We also prefer to undercut the under surface of the ring, as shown at 35, to prevent oil from creeping back and dropping through the neck ring.

We have found the above construction very efficient in preventing the deposit of carbon upon the bottom and walls of the fire box, particularly if the inner end of the atomizer is elevated slightly above the bottom of the fire box. We have also found that a ring, having the construction described above, will remain in operation over very extended periods of time without having carbon deposits formed thereon, and that the contour of this ring is such as to assure very complete mixture of the air and fuel so that the fuel is practically completely burned.

While we have shown the details of the preferred embodiment of our invention, it is to be clearly understood that our invention is not limited to these details of construction, and it is also to be understood that our invention is not limited to use with an atomizer of the construction shown in the accompanying drawing, but may be used with an atomizer in which separate means are employed for supplying air thereto. Other adaptations and modifications of our invention within the scope of the appended claims will occur to those skilled in this art.

Having thus described our invention, what we claim is:

1. The combination with a rotary tubular shaped outwardly flaring atomizer having radially extending fan blades carried by the outwardly flaring portion thereof, of means for controlling the supply of air to the oil spray formed by said atomizer comprising a neck ring surrounding said atomizer and spaced therefrom, a sleeve adjustably mounted in said neck ring, the upper edge of said sleeve being notched to provide a plurality of spaced teeth, the inner edges of which are beveled outwardly, and an air controlling ring having a substantially flat under surface provided with an annular beveled rib for resting upon the beveled surfaces of said teeth, the opening in said ring being slightly larger than the diameter of said fan blades, the upper face of said ring having an annular depression formed therein, the inner edge of which is lower than the outer edge, the radius of the curvature of said depression being substantially equal to the diameter of said atomizer at its atomizing edge and the outer diameter of said depression being but slightly less than twice said diameter of said atomizer, said ring being beveled outwardly and downwardly from the outer edge of said depression.

2. The combination with a rotary tubular shaped outwardly flaring atomizer having fan blades carried by the outwardly flaring

portion thereof, of means for controlling the supply of air to the oil spray formed by said atomizer comprising a neck ring surrounding said atomizer and spaced therefrom, a sleeve adjustably mounted in said neck ring, and an air controlling ring having a substantially flat under surface resting upon said sleeve, the opening in said ring being slightly larger than the diameter 10 of said fan blades, the upper face of said ring having a broad annular depression formed therein, the inner edge of which is lower than the outer edge, the radius of the curvature of said depression being substantially equal to the diameter of said atomizer at its atomizing edge the outer edge of the depression being at a substantial distance outwardly from the nozzle.

3. The combination with a rotary tubular shaped outwardly flaring atomizer and means for supplying air thereto, of means for controlling the supply of air to the oil spray formed by said atomizer comprising an air controlling ring having an opening 20 therein, the upper face of said ring having an annular depression formed therein, the outer edge of which is higher than the inner edge and is at substantially the level of the discharge edge of the nozzle, the radius of 25 the curvature of said depression being substantially equal to the diameter of said atomizer at its atomizing edge, and the outer diameter of said depression being at a spaced distance outwardly from the discharge edge 30 of the nozzle.

4. The combination with a tubular shaped outwardly flaring atomizer having fan blades carried by the outwardly flaring portion thereof, of means for controlling the supply 40 of air to the oil spray formed by said atomizer comprising a ring surrounding said atomizer in spaced relation to said fan blades, said ring having a depression formed in its upper surface for directing the air discharged from said fan blades upwardly and into the oil spray formed by said atomizer at points lying on a circle, the diameter of which is somewhat less than twice the diameter of said atomizer at its atomizing 45 edge.

5. The combination with a fire box having an opening formed in one wall thereof, of a rotary atomizer extending through said opening, means for supplying air to the 55 spray formed by said atomizer, and means for directing said air into said spray and for preventing said spray from contacting with said wall comprising a ring surrounding the inner end of said atomizing nozzle 60 and having a depression formed therein, said depression flaring outwardly and upwardly to discharge the air into the spray at a spaced distance outwardly from its discharge from the nozzle.

65 6. A fuel oil burner comprising, in com-

bination, an outwardly flaring rotary atomizing nozzle, an air ring disposed around the nozzle at its discharge end, means for creating an outward flow of air between the ring and the nozzle, the upper surface of the ring 70 adjacent the nozzle extending outwardly at level below the discharge edge of the nozzle to carry the air flow horizontally outwardly beneath the oil spray from the nozzle but, at a spaced distance outwardly from the 75 discharge edge of the atomizer, curving upwardly to an annular ridge at a height substantially at the level of the discharge edge of the nozzle to direct the air flow into the spray at a point where the spray has been 80 thinned by its increasing circumference, for lifting the oil film.

7. A fuel oil burner comprising, in combination, an outwardly flaring rotary atomizing nozzle, an air ring surrounding the 85 discharge end thereof, and means for inducing an air flow between the nozzle and the ring, the ring having a broad upper surface for carrying the air flow horizontally outwardly from the discharge edge of the nozzle below and substantially parallel with the oil spray therefrom and, at a spaced distance outwardly from the discharge edge, having an upwardly inclined contour for 90 directing the air flow upwardly into the 95 oil spray.

8. In an oil burner, the combination of a rotary atomizing nozzle throwing off a spray of fuel oil under centrifugal force from its discharge edge, an air ring disposed around the discharge end of the nozzle, means for creating a forced flow of air between the ring and the nozzle, the ring extending horizontally outwardly below the discharge edge of the nozzle and being 100 curved upwardly at its outer edge to form a ridge approximately at the level of the discharge edge but spaced outwardly therefrom for directing the air into the spray at the region of the ridge.

9. In an oil burner, the combination of a rotary atomizing nozzle throwing off a spray of fuel oil under centrifugal force from its discharge edge, an air ring disposed around the discharge end of the nozzle, means for creating a forced flow of air between the ring and the nozzle, the ring extending horizontally outwardly below the discharge edge of the nozzle and being curved upwardly 115 at its outer edge to form a ridge approximately at the level of the discharge edge but spaced outwardly therefrom for directing the air into the spray at the region of the ridge, the air ring beyond said ridge being beveled downwardly for directing 120 backward eddy currents of air upwardly into the spray at the region of the ridge.

10. An oil burner comprising an annular ring, a rotary atomizing nozzle discharging a film or spray of oil under centrifugal 130

force, means for forcing a current of air between the nozzle and the ring, the ring having a broad upper surface for carrying the air current horizontally outwardly beneath the oil spray and in direct contact with the under side thereof, said surface of the ring being curved upwardly about its outer edge to direct the air current into the oil spray at a region spaced outwardly beyond the discharge edge of the nozzle.

11. An oil burner comprising an annular ring, a rotary atomizing nozzle discharging a film or spray of oil under centrifugal force, means for forcing a current of air between the nozzle and the ring, the ring having a broad upper surface for carrying the air current horizontally outwardly beneath the oil spray and in direct contact with the under side thereof, said surface of the ring being curved upwardly about its outer edge to direct the air current into the oil spray at a region spaced outwardly beyond the discharge edge of the nozzle but slightly less than the radius of the discharge edge of the nozzle.

12. An oil burner comprising, in combination, a tubular outwardly flaring rotary atomizing nozzle, fan blades on the exterior of the nozzle beneath the flaring mouth thereof, a neck ring forming the central margin of an annular firebed, an air ring disposed about the nozzle and supported on the neck ring and vertically adjustable relatively to the fan blades whereby a greater or smaller portion of the air current created by the fan blades may be discharged onto the top surface of the ring, the ring having a broad surface extending outwardly beyond the discharge edge of the nozzle for carrying the air current horizontally outwardly beneath the oil spray and radially beyond said surface having an upwardly contoured surface for then directing the air current upwardly into the oil spray after the spray has been thinned by its increased radius after leaving the discharge edge of the nozzle.

13. An oil burner comprising, in combination, a firebed having a central opening, a rotary atomizing nozzle extending therethrough for discharging an annular spray of oil across the bed, an air ring disposed around the nozzle at its discharge end, means for creating a forced air draft between the nozzle and the ring, the upper surface of the ring having a broad, horizontal annular surface about the nozzle and radially there beyond having an upwardly inclined annular surface to carry the forced air outwardly and then upwardly into the oil spray, means for admitting a natural draft beyond the outer edge of the ring for supplying additional air to the mixed oil and air and for keeping the fire and oil off the bottom of the firebed.

14. An oil burner comprising, in combination, a firebed having a central opening, a rotary atomizing nozzle extending therethrough for discharging an annular spray of oil across the bed, an air ring disposed around the nozzle at its discharge end, means for creating a forced air draft between the nozzle and the ring, the upper surface of the ring having a broad, horizontal annular surface about the nozzle and radially there beyond having an upwardly inclined annular surface to carry the forced air outwardly and then upwardly into the oil spray, means for forming air passages for a natural draft leading into the region above the firebed beyond the outer edge of the air ring, and closures for said passages, the air ring being vertically adjustable for increasing or diminishing the volume of forced draft directed across the air ring and the closures being connected with the ring for opening the passages when the ring is moved to a position of diminished forced draft.

15. An oil burner comprising a horizontally disposed fire pot having a central opening, vertically journaled tubular outwardly flaring rotary atomizer, protruding through the central opening of the fire pot, radial fan vanes carried on the under side of the lip of the atomizer for generating a substantially horizontal outward flow of air from beneath the oil film discharged by the atomizer, an air ring covering said opening, the inner edge of the air ring forming with the lip of the atomizer a discharge constriction for the primary air supply from the fan vanes, and the outer edge of the ring forming with the inner edge of the fire pot a passageway for a secondary supply of air by suction or gravity, the upper surface of the ring at its outer region being inclined downwardly to its outer edge to cause a portion of the primary air flow to hug the floor of the fire pot whereby the aspirating effect of the lower strata of the primary air flow aspirates the secondary air flow through its said passage.

16. An oil burner comprising a fire pot forming the bottom of a combustion chamber and having a central opening, a vertically journaled rotary centrifugal atomizer having an outwardly flaring discharge end protruding through the opening in the fire pot and carrying radial fan vanes beneath the discharge lip for generating a substantially horizontal outward flow of air, a ring surrounding the atomizer beneath its lip, the air flow being directed over the upper surface of the ring, the upper surface of the ring at its outer edge being downwardly inclined, and an auxiliary air inlet passage formed between the outer lower edge of the ring and the fire pot.

17. A fuel oil burner comprising a vertically journaled rotary centrifugal atomizer

horizontally discharging a spray of oil, centrifugal fan vanes below the discharge edge of the atomizer for supplying a horizontal air current beneath and in contact with the oil spray, and an annular air directing ring surrounding the atomizer below the discharge edge, and forming an air discharge opening between it and the discharge edge, the upper surface of the ring being annularly profiled to provide a relatively broad outward air directing surface and, at an annular region radially beyond the discharge edge of the atomizer, curving upwardly and outwardly to lift the air current.

In witness whereof, we hereunto subscribe our names this 21st day of April, 1923.

FRANKLIN HARDINGE.
BENJAMIN H. CONNOR.
